DESIGN FOR A GRAND PIANO

Everett Worthington, Scarsdale, N. Y., assignor
to Story & Clark Piano Company, Chicago, Ill.,
a corporation of Delaware

Application February 8, 1938, Serial No. 74,970

Term of patent 7 years

To all whom it may concern:

Be it known that I, Everett Worthington, a citizen of the United States and resident of Scarsdale, in the county of New York and State of New York, have invented a new, original, and ornamental Design for a Grand Piano, of which the following is a specification, reference being had to the accompanying drawing, forming a part thereof.

Fig. 1 is a perspective view of a grand piano with the rear top cover shown raised, showing my new design, with the inside or lower cover shown in solid black lines.

Fig. 2 is a top plan view of the grand piano

with the rear top cover shown in closed position, and with the inside or lower cover shown in solid black lines, and

Fig. 3 is a fragmentary vertical sectional view thereof on an enlarged scale, on line 3—3 in Fig. 2 of the drawing, with the rear top cover omitted, showing the inside or lower cover in edge elevation in solid black lines.

The dominant features of my design are shown in full lines.

I claim:

The ornamental design for a grand piano, as shown and described.

EVERETT WORTHINGTON.
